Primary Examiner — Elizabeth A. Albert(74) *Attorney, Agent, or Firm* — Hauptman Ham, LLP(57) **CLAIM**

I claim the ornamental design for a flowerpot pen stand, as shown and described.

DESCRIPTION

FIG. 1 is a perspective view of a flowerpot pen stand showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded perspective view thereof in which the base is placed above the flowerpot;

FIG. 9 is an exploded perspective view of FIG. 1; and,

FIG. 10 is an assembled perspective view thereof.

The long broken lines in FIGS. 1-5 and 8-10 and the dotted lines in FIG. 10 show features in the environment that form no part of the claimed design.

The broken lines in FIG. 7 are included to show part of the flowerpot pen stand that forms no part of the claimed design.
